UNITED STATES PATENT OFFICE

JOSEPH D. WOOD, OF WOLLASTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

SWITCH-OPERATING MECHANISM

Application filed June 30, 1926. Serial No. 119,770.

This invention relates to manually controlled operating mechanisms for electric switches and has for an object the provision of an operating mechanism including an operating handle by which the switch is adapted to be closed, with means for locking the handle and thereby the switch in switch closed position and so arranged that the unlocking of the handle effects the prior opening of the switch, so that the switch can open at its own speed and independently of the handle.

A further object is generally to improve the construction of switch operating mechanisms.

The broader principle of this invention is disclosed and claimed in my co-pending application Serial No. 113,790, filed June 4, 1926.

Fig. 1 is a side elevation of a switch operating mechanism embodying this invention associated with an electric switch.

Fig. 2 is a front elevation of the switch operating mechanism of Fig. 1.

Fig. 3 is a detail of the operating mechanism just after the switch has been tripped and has opened and while the handle is yet locked to the face plate.

As here shown, the switch operating mechanism embodying the invention is carried by a face plate 10 which is adapted to be secured to a panel or other suitable support 12. The electric switch 14 may be of any suitable or desirable construction and may also be secured to said support 12 opposite said face plate. A horizontally reciprocable switch operating member or rod 16 is connected with the switch mechanism and is extended through said support and face plate for connection with the switch operating mechanism embodying this invention.

The switch operating mechanism as here shown comprises an operating handle formed of a pair of spaced bars 18 which are pivoted at their lower ends to a forwardly directed extension 20 of the face plate 10. The upper end of said bars are fixed to a handle grip 22. Said switch operating rod 16 is connected to the operating handle through a breakable connection which in-

cludes a pair of spaced triangularly-shaped toggle-plates 24 which are disposed between the handle bars 18 and are pivoted at their forward lower corners on the pin 26 carried by and extended between said bars. The 55 operating rod 16 is pivotally connected to the lower rear corner of said plates by the pin 28. The upper corner of said plates has a pin 30 extended therethrough on which a latch roller 32 is loosely journalled. The 60 handle bars are provided with rearwardly extended depending projections 34 between which a latch 36 is loosely disposed on the pin 38. Said latch is provided at its forward end with a recess 40 into which the 65 latch roller 32 is adapted to be received whereby to lock the switch operating rod releasably with the handle. When the latch 36 is depressed by rotating it in a counterclockwise direction, it is caused to be disengaged from the movable latch roller whereby to permit the switch to open. Said latch 36 is normally biased to latching position either by gravity or by a spring not shown, and a movement of the switch handle in a counterclockwise direction to open circuit position serves to effect the re-engagement of the latch and the toggle-plates 70 in the usual manner so that the switch can again be closed by a movement of the operating handle into the position illustrated.

The operating handle is provided with means to lock it releasably in the switch closed position to the face plate. Said means includes a handle locking latch 42 which is 80 pivoted at 44 to the upper end of the face plate between a pair of spaced forwardly extending plates formed integral therewith and extends forwardly thereof and is adapted releasably to engage a latch roller 46 disposed between and loosely mounted on a pin 48 connecting the depending projections 34 of said operating handle. Said latch 42 is biased for handle locking position by suitable means as a spring 50. When said handle locking latch is depressed it is caused to release its hold on the operating handle whereby to permit the handle to move in a counterclockwise direction about its pivot to a switch open position. Said latch is adapted to be 90 100

depressed by means including a thumb button 52 disposed in a recess 54 in the upper part of the handle grip 22 and normally elevated thereabove.

- 5 A coil compression spring 56 is disposed in said recess beneath said button to hold it normally in elevated and latch free position. A trip rod 58 is affixed to said button 52 and extends downwardly through said handle grip into the space between the handle bars 18 and is provided at its lower end with an enlargement or head 60 which is disposed above and in a position to engage the forward projection 62 of said handle locking latch. 10 Normally said spring 54 serves to maintain said head 60 in elevated position free from engagement with said latch. When said thumb button 52 is depressed said head 60 is moved downwardly into engagement with the latch whereby to depress it and free it from its holding engagement with the operating handle, thereby to permit said handle to be moved to switch open position. 15

In accordance with this invention means 20 are provided to trip the switch prior to the complete release of the operating handle so that the switch can move to open position at its own speed independent of and not retarded by the operating handle. To this end, said trip rod 58 is provided with an extension 64 which is disposed beneath said head 60 and terminates above and normally free of and in position to engage and depress the switch latch 36 so that when said thumb button 52 is depressed, the switch latch 36 is caused to be disengaged from the toggle plates 54 thereby to permit the switch to open independently of the handle. The lower end of said extension 64 is adapted to be disposed immediately above the switch latch 36 while the head 60 is adapted to be disposed considerably above the handle locking latch 42 in the normal switch closed position of the parts. With this disposition, when the thumb button 52 is depressed, the extension 54 is moved into engagement with the switch latch 36 and completely frees it from the toggle plates before the head 60 has been moved downwardly far enough to effect the complete release of the locking latch 42 from the handle. Under these conditions, the switch is tripped open prior to the complete unlocking of the handle so that the switch opens at its own speed independently of manual control. 55

It will be noted that the switch latch 26 can be tripped independently of the operation of the thumb button, so that the switch can be opened automatically on overload.

60 I claim:

1. An electric switch operating mechanism including the combination of a switch operating member, means to hold said member releasably in switch closed position, an actuating handle for said switch operating mem-

ber, means to hold said actuating handle releasably in switch closed position and tripping means engageable in succession with said switch holding and handle holding means in the order named whereby to release both holding means in succession, said switch holding means having provision for releasing said switch operating member independently of said tripping means. 70

2. Electric switch operating mechanism including the combination of a switch operating member, means including a latch to hold it in switch closed position, an actuating member for said switch operating member, means including a latch to hold it in switch closed position, and tripping means arranged to operate said latches in successive order, said first latch having provision for being tripped independently of said tripping means. 75

80 3. Electric switch operating mechanism including the combination of a switch operating member, means including a latch to hold it in switch closed position, an actuating member for said switch operating member, means including a latch to hold it in switch closed position, and tripping means arranged to operate said latches in successive order and actuate the switch latch first whereby to effect the opening of the switch independently of the actuating member, said first latch having provision for being tripped independently of said tripping means. 85

90 4. Electric switch operating mechanism including the combination of an actuating member, means to lock it releasably in switch closed position, a switch operating member having a breakable connection with said actuating member, and tripping means arranged to engage and break said breakable connection and subsequently to engage and release the locking means for the actuating member, said breakable connection having provision for being broken independently of said tripping means. 100

105 5. Electric switch operating mechanism including the combination of an actuating member, means to lock it releasably in switch closed position, a switch operating member having a breakable connection with said actuating member, and tripping means carried by said actuating member arranged to engage and break said breakable connection and subsequently to engage and release the locking means for the actuating member, said breakable connection having provision for being broken independently of said tripping means. 110

115 6. Electric switch operating mechanism including the combination of an actuating member, means including a latch to lock said actuating member releasably in switch closed position, a switch operating member, a toggle connecting said actuating and operating members, means including a latch to lock said toggle set, member and tripping means ar- 120

ranged to engage and depress said latches in successive order.

7. Electric switch operating mechanism including the combination of an actuating member, means including a latch to lock said actuating member releasably in switch closed position, a switch operating member, means including a latch to lock said operating member releasably with said actuating member, and means independent of said latches carried by said actuating member arranged to engage and depress said latches in successive order.

8. Electric switch operating mechanism including the combination of an actuating handle, depressible means to lock said handle releasably in switch closed position, a switch operating member, depressible means to lock said switch operating member releasably to said handle, tripping means for both said locking means independent thereof including a thumb button carried by said handle, and means actuated by the depressing of said thumb button to depress and release both said holding means in succession.

9. Electric switch operating mechanism including the combination of an actuating handle, means to lock said handle releasably in switch closed position, a switch operating member, including a normally straightened toggle means to lock said switch operating member releasably to said handle comprising a latch arranged to hold said toggle in straightened condition, and tripping means for said locking means and latch including a thumb button carried by said handle and means actuated by the depressing of said thumb button to engage and release said holding means and latch in succession, said tripping means operable to release said latch first.

10. Electric switch operating mechanism including the combination of an actuating handle, a latch to lock said handle releasably in switch closed position, a switch operating member, means including a second latch disposed beneath said first latch to lock said switch operating member releasably to said handle, and tripping means for said latches independent thereof including a tripping rod carried by the handle and terminated thereabove and disposed in position to be depressed into operative engagement with both latches.

11. Electric switch operating mechanism including the combination of an actuating handle, a latch to lock said handle releasably in switch closed position, a switch operating member, means including a second latch disposed beneath said first latch to lock said switch operating member releasably to said handle, and tripping means for said latches independent thereof including a tripping rod carried by the handle and free of and terminated thereabove and disposed in position to be depressed into engagement with both latches, said tripping rod constructed and ar-

ranged to engage and depress the switch latch first and thereafter to engage and depress said handle holding latch.

12. Electric switch operating mechanism including the combination of an actuating handle, a depressible latch to hold said handle releasably in switch closed position, a switch operating member, means including a depressible switch latch disposed beneath said handle latch to lock said switch operating member releasably to said handle, and tripping means for said latches including a tripping rod carried by the handle and terminated at its upper end above said handle and at its lower end immediately above and free from operative engagement with said switch latch and having an extension disposed above said handle latch, said tripping rod constructed and arranged when depressed to depress said switch latch and thereafter to move its extension into engagement with said handle latch whereby to depress it subsequent the depression of said handle latch.

In testimony whereof, I have signed my name to this specification.

JOSEPH D. WOOD.
